DESIGN FOR A GAME BOARD

Henry Overend, Liverpool, England

Application October 4, 1944, Serial No. 115,608

Term of patent 14 years

(Cl. D34—5)

To all whom it may concern:

Be it known that I, Henry Overend, a subject of the King of Great Britain residing at Liverpool, England, have invented a new, original, and ornamental Design for a Game Board, of which the following is a specification, reference being had to the accompanying drawing, forming a part thereof.

In the drawing:

Fig. 1 is a top plan view of a game board, showing my new design, and

Fig. 2 is a front elevational view of the same.

I claim:

The ornamental design for a game board, as shown.

HENRY OVEREND.
